(Cl. D58—17)

To all whom it may concern:

Be it known that we, Robert L. Holland and Walter F. Nessen, citizens of the United States, residing at Chicago, in the county of Cook and State of Illinois, have invented a new, original, and ornamental Design for a Container for Cooking Utensils, Food, or the like, of which the following is a specification, reference being had to the accompanying drawing, forming a part thereof:

In the drawing:

The single figure is a perspective view of a container for cooking utensils, food, or the like, showing our new design. The opposite end and side are similar respectively to the end and side shown, and the bottom is plain.

We claim:

The ornamental design for a container for cooking utensils, food, or the like, substantially as shown and described.

ROBERT L. HOLLAND.
WALTER F. NESSEN.
